UNITED STATES PATENT OFFICE.

GEORGE H. GILMAN, OF CLAREMONT, NEW HAMPSHIRE, ASSIGNOR TO CLAREMONT MACHINERY COMPANY, OF CLAREMONT, NEW HAMPSHIRE, A CORPORATION OF MASSACHUSETTS.

DRILLING APPARATUS.

1,303,790.

Specification of Letters Patent. Patented May 13, 1919.

Application filed January 6, 1914. Serial No. 810,663.

To all whom it may concern:

Be it known that I, GEORGE H. GILMAN, a citizen of the United States, and a resident of Claremont, in the county of Sullivan and 5 State of New Hampshire, have invented an Improvement in Drilling Apparatus, of which the following description, in connection with the accompanying drawings, is a specification, like characters on the drawings representing like parts.

This invention relates to earth boring apparatus, and more especially to supports for rock drilling machines of the type in which the drill is manipulated, held up to the 15 work, and withdrawn therefrom under manual guidance and pressure exerted by the operator and applied directly to the body of the tool, as distinguished from rigidly mounted drills which are fed by mechanical means.

My invention will be best understood by reference to the following specification when taken in connection with the accompanying drawings of one specific embodiment there- 25 of, while its scope will be more particularly pointed out in the appended claims.

In the drawings:

Figure 1 is a rear elevation, partly in vertical section, of a drill and drill-mounting 30 embodying my invention;

Fig. 2 is a side elevation of the same, showing, in full and dotted lines, two positions assumed by the drill and its mounting in drilling a hole, this view illustrating also, 35 in a conventional way, the floor, wall and roof of a portion of a mine.

Referring to the drawings and to the embodiment of my invention which I have selected for illustration, I have there shown 40 an earth boring apparatus comprising a rock drilling machine 5, and a support 6 upon which it is mounted in such a manner as to sustain the weight of the machine and steady it in operation, while providing for 45 free lateral movement of the drilling machine and its support, accompanied by relative angular and vertical movement of the machine and support under the manual guidance of the operator whereby the drill 50 bit may be caused to feed into the hole in a perfectly straight line and without danger of cramping, bending or breaking, due to changes which would otherwise take place in angular position of the drill-bit as it 55 progresses into the drilled hole.

The drilling machine itself may be of any appropriate type, but herein is a familiar form of hammer type of rock drill having a cylinder 7 within which a hammer piston 8 reciprocates and is provided with a reduced forward extension or hammer bar 9, which delivers a succession of blows upon the inner end of a drill bit 10. The latter, by preference, will be held in a chuck having an automatic rotating mechanism, and the drill bit itself may be of twisted or helical form as shown. It will be understood, however, that other equivalent or substitute devices may be employed, and it will be unnecessary further to describe the drill bit 70 and its chuck since these parts form no essential part of my present invention.

Any appropriate manipulating means may be provided whereby the operator may grasp and control the direction and feed 75 of the drill, but herein I have provided, at the rear of the cylinder, a pair of grasping handles 11 which extend laterally in opposite directions and serve as convenient handles to enable the operator to manipulate 80 the tool. The latter may be provided as usual with one or more, herein a pair, of tie-rods 12, 12.

The drill support may be of any other construction suitable to perform its intended 85 functions, but herein comprises a plurality of vertically disposed and telescopically arranged members, herein three in number designated by the numerals 13, 14 and 15. The member 13 may be termed a gooseneck, 90 as it is herein provided with a laterally offset portion 16 provided with an eye 17 preferably placed in line with the axis of the shank of said member. Secured to this eye is a depending hook 18 hooked onto one of the side rods 12 of the drilling machine so that the latter is freely pendant and is capable of being swung vertically as well as horizontally.

The shank portion of the member 13 extends within a member 14 which latter, in the present instance, is in the form of a tube provided adjacent its upper terminal portion with a set screw 19 one purpose of which is adjustably to secure the member 13 100 in the desired position of vertical adjustment. Preferably the member 13 is provided with a longitudinal groove 20 to receive the point of the set screw 19. The set screw when thus engaging the groove serves 105 110

as a means for preventing the member 13 from turning about its vertical axis with relation to the member 14. As a means for preventing the member 13 from being accidentally withdrawn from the member 14, the groove 20 is made of such length as to terminate at a point 21 somewhat above the lower end of the member 13.

The member 14 extends within the member 15, and the latter is herein tubular in form to receive a helical spring 22 which serves yieldingly or resiliently to support the drill for a purpose which will presently appear. The lower end of the spring 22 rests on the bottom of the chamber formed within the member 15, while the member 14 in turn rests upon the upper end of the spring. The member 14 is herein provided with a longitudinal groove 23 terminating at a point 24 above the bottom of said member, and this groove receives a set screw 25 which serves to prevent relative turning movement of the members 14 and 15, as well as to prevent one from being accidentally withdrawn from the other, and, if desired, may serve further as a means adjustably to secure the two members in various vertical relations one to the other. Usually, when the apparatus is in use, however, the set screw 25 will be loosened just sufficiently to allow the member 14 to slide freely within the member 15 in order that the spring may sustain the weight of the parts supported thereby, including the rock drill.

The lower-terminal portion of the member 15 is preferably in the form of a spur 26 adapted to enter the ground and secure a firm hold therein in order that it may be prevented from slipping laterally. Preferably, also, as a means for limiting the extent to which the spur can enter the ground, there will be provided a vertically adjustable stop, herein in the form of a collar 27 adjustably secured to the member 15 by means of a set screw 28.

Drills of the type illustrated are commonly known as self-rotating hand hammer drills and have heretofore been supported and manipulated by the operator without any mechanical support or mounting. In handling such drills, however, it has been found in practice very difficult to hold the drill steady and keep it up to its work in the proper manner. As a means for steadyng the drill and sustaining its weight while still allowing the same to be moved freely under the manual guidance of the operator, I have provided the described support which possesses also the advantage of being light and portable. In drilling a hole, the support is first adjusted to the correct height by means of the described adjusting devices and is so placed as to incline rearwardly, that is to say, toward the operator who stands at the rear of the machine. The operator, then

placing the end of the drill bit against the wall of the mine, starts the machine into operation, exerting sufficient forward pressure to cause the drill bit to be fed into the hole as the cutting operation proceeds. It must be evident that, as the hole deepens, the drill support will swing forwardly from the position shown in full lines in Fig. 2 to the position indicated in dotted lines, and that during such movement the angular relation between the tool and its support will constantly change. It must also be evident that owing to the swinging motion of the support the tool would tend to move in the arc of a circle and would thus change the angular relation of the drill bit with respect to the drilled hole. In order to prevent this tendency, as the support swings forwardly toward a vertical position, the operator will exert a sufficient downward pressure upon the handles 11 to counteract the tendency of the machine to depart from a straight, true course, and after the support has passed beyond a vertical position, the operator will gradually diminish the downward pressure exerted upon the handles and thus permit the machine to rise under the influence of the supporting spring. It will be evident that by a proper apportionment of the strength of the spring to the weight of the machine, and by a proper control upon the spring through the grasping handles of the machine, the latter may be caused to travel in a straight, true course and the drill bit fed into the hole without cramping, bending, or breaking. The drill bit will, of course, be withdrawn from the hole by a reversal of the foregoing operation.

By my improved construction described above, it will be noted that a lightened and simplified device is produced which is not only adapted to rough usage, but which may be very cheaply manufactured, as the parts are not only simple in form but the finishing of the same is reduced to a minimum. During the process of placing the drill in position for spotting or collaring a hole, it is also entirely unnecessary for the drill to be operating, thereby greatly facilitating that operation. Through the provision of the set screws 19 and 25, it is also possible for the operator to provide a rigid support during the collaring operation, if desired. It will also be evident that in my improved construction wherein my improved automatically acting mechanical means are provided for varying the length of the support, it is entirely unnecessary to provide any connection to the air line or any controlling means for that connection, it only being necessary to release the lower set screw after the collaring operation in order to enable the drill to be readily adjustable to any height under control of the operating handle, both of the operator's hands thereafter being free for

use on the handle. Attention is also directed to the fact that through the provision of my improved off-set support and the flexible means for supporting the drill in pendant position thereon, the drill is normally balanced and the operator is also free to adjust the same in any manner desirable to enable him to maintain the alinement of the hole. It should also be observed that through the provision of my improved supporting connection adapted to be connected to the side rod of the drill, it is possible quickly to attach or detach a drill of standard construction to the supporting means, or if desired to shift the drill bodily longitudinally relative to its support. These and other advantages of my improvement will, however, be clearly apparent to those skilled in the art.

20 While I have herein shown and described one specific embodiment of my invention for illustrative purposes and have disclosed and discussed in detail the construction and arrangement incidental to one specific application thereof, it is to be understood that the invention is limited neither to the mere details or relative arrangement of parts nor to the specific embodiment herein shown, but that extensive deviations from the illustrative form or embodiment of the invention may be made without departing from the principles thereof.

Having thus described one embodiment of my invention what I claim and desire to secure by Letters Patent is:

35 1. An earth boring or rock drilling apparatus including a two-part support, a trans-

versely disposed tool pivotally mounted thereon, and resilient mechanical means operatively connected between the parts of said support for varying the effective height thereof as the tool is moved longitudinally.

2. An earth boring or rock drilling apparatus including a telescopic support, a transversely disposed tool pivotally mounted thereon, and resilient mechanical means housed in said support for varying the effective height of said support as said tool is moved longitudinally.

3. An earth boring or rock drilling apparatus comprising a boring or drilling tool, an overhanging support therefor movable about one of its ends as a pivot, and a single pendant supporting connection pivotally connected to said support and slidably connected to said tool at a point between its ends.

4. An earth boring or rock drilling apparatus comprising, in combination, a boring or drilling tool, and supporting means therefor including a plurality of coaxially disposed telescopically arranged spring-pressed members, and a vertically adjustable off-set member carried by one of the same upon which said tool is pivoted with its pivot disposed at a point adjacent the vertical axial line of said members.

In testimony whereof, I have signed my name to this specification, in the presence of two subscribing witnesses.

GEORGE H. GILMAN.

Copies of this patent may be obtained for five cents each, by addressing the "Commissioner of Patents, Washington, D. C."

It is hereby certified that the assignee in Letters Patent No. 1,303,790, granted May 13, 1919, upon the application of George H. Gilman, of Claremont, New Hampshire, for an improvement in "Drilling Apparatus," was erroneously described and specified as "Claremont Machinery Company, of Claremont, New Hampshire, a corporation of Massachusetts," whereas said assignee should have been described and specified as *Sullivan Machinery Company, a corporation of Massachusetts*, as shown by the records of assignments in this office; and that the said Letters Patent should be read with this correction therein that the same may conform to the record of the case in the Patent Office.

Signed and sealed this 22d day of July, A. D., 1919.
